AIR CONDITIONING UNIT

Fred M. Young and Edward H. Stempel, Racine,
Wis.; said Stempel assigner to Young Radiator
Company, Racine, Wis.

Application August 8, 1938, Serial No. 223,581

6 Claims. (Cl. 62—140)

The present invention refers to an air conditioning device wherein the mechanism is all contained in a single cabinet which may be placed in the room to be served.

5 One of the objects of the present invention is to provide a self-contained air conditioner which may be manufactured in individual sections then shipped and assembled in the room to be served or otherwise.

10 Another object of the present invention is to provide an individual room serving air conditioner wherein the conditioned air is discharged horizontally a considerable distance from the floor or near the ceiling and the return air caused 15 to enter the cabinet a considerable distance below the discharge point or at the floor thus to provide a complete movement of all of the air in the room.

A still further object of the present invention is 20 to provide an air conditioning unit wherein the compressing and condensing mechanism is positioned within a separate compartment or enclosure.

Another object of the present invention is to 25 provide grille outlets in the top of the unit and deflector blades which are positioned on the inlet side of the grilles, the deflectors being bendable whereby they may be positioned to thereby discharge the air fan-like or in any desired direction.

To these and other useful ends my invention consists of parts, combinations of parts, or their equivalents, and mode of operation, as herein-after set forth and claimed and shown in the 30 accompanying drawings in which:

Fig. 1 is a front elevation of our improved unit having one half of the front sectioned on line 1—1 of Figure 2.

Figure 2 is a side elevation of the device illustrated in Figure 1 having all of the front removed on line 2—2 of Figure 1.

Fig. 3 is a fractional front elevation of a modification having one half of the front panel and access door removed on line 3—3 of Figure 4.

45 Fig. 4 is a fractional side elevation of the device illustrated in Figure 3 having a portion of the near panel removed on line 4—4 of Figure 3.

Fig. 5 is a detail top view of the outlet grille illustrating the air direction blades in a position to discharge the air slightly fan-like.

Fig. 6 is a front elevation of the grille illustrated in Figure 5.

Fig. 7 is a transverse sectional view of the grille taken on line 7—7 of Figure 6.

Fig. 8 is a sectional view of a room having our improved cabinet positioned therein and illustrating the air travel brought about by the design in Figures 3 and 4.

Fig. 9 is a diagrammatic drawing illustrating 5 the entire mechanism of the modification as illustrated in Figures 3 and 4 and indicating by arrows the direction of air travel from the time it enters until it leaves the unit.

Fig. 10 illustrates a modification of the design 10 shown in Figures 1 and 2.

As thus illustrated in Figures 1 and 2 our invention consists preferably of a housing having four compartments designated by reference characters A, B, C and D. Each of these compartments may be formed into separate units and detachably secured together. However, as illustrated, sections A and B are made in a single unit and sections C and D are detachably secured together and to this unit. Sections A 15 and B comprise a rear panel 5, a bottom 6, front panel 7 and side panels 8 and 9 forming a complete inclosure for the condenser unit and the evaporator.

The condenser in its entirety is designated by 25 reference character E and the evaporator unit in its entirety is designated by reference character F. Unit E comprises a bottom circular member 10 and a top member 11, these two members being secured together by means of a gasketed 30 joint 12. We provide preferably four supporting legs 13, each being mounted on rubber seats 14, the seats being positioned as illustrated in channels 15.

We position in unit E a motor, compressor, 35 condenser and the necessary connections whereby the unit is complete and capable of supplying liquid condensate to evaporator F. The various connections and parts are preferably similar to those illustrated diagrammatically in Figure 9.

We provide a partition ceiling 18 having a suitable covering whereby chambers A and B are insulated one from another. Evaporator F is secured to an outlet duct 19 which is secured 45 to partition 20 and registers with an opening therein. Evaporator F consists of the usual coil of tubes and closely spaced fins through which the tubes extend, the entire assembly being surrounded horizontally by an inclosure 21. Member 19 is made suitable for the reception of a steam coil as will hereinafter appear.

We provide a grille 22 in the front panel 1 of unit B whereby the air may enter this grille and pass up between the tubes and fins and into 50 55

chamber C through duct 18. We provide a drip pan 23 having a drain outlet 24 and a removable front panel 16 to thereby provide convenient access to chamber A.

5 Unit C comprises a rear panel 30 and a front panel 31 having a removable lid or door 32 and side panels 33 and 34. Unit D comprises a rear panel 35, side panels 36 and 37 and a front grille 38 which is removably secured to the unit as illustrated. Units C and D are separated by a partition 39. It will be understood that this partition may either be a part of section C or a part of section D, and that partition 28 may be a part of the construction forming either unit B or C. 15 Section D is provided with a lid 40 which is preferably removably secured to the section as illustrated.

We provide a blower fan 41 which is preferably of the cage type as illustrated, the outlet 42 being secured to and registering with an opening in partition 39.

We provide a motor 43 which is either supported on partition 28 or in any other convenient place in chamber C. An operating connection is made between the motor and fan by means of a belt 44.

We provide deflector blades 45 on the rear of grille 38 which are adapted to form holding means for the grille blades 51 (see Figure 5). These 30 blades are adapted to be easily bent so they may be positioned to discharge the air into the room in any desired direction or fan-like. We preferably provide a deflector plate 49 to thereby assist in directing the air from the fan into the grilles. 35

It will be seen that we have provided a cabinet having four compartments, the bottom compartment having a complete compressor and condensing device, section B having an evaporator and being connected to the compressor as clearly 40 illustrated in Figure 9.

It will be noted that we provide means for moving air from the room into grille 22 through the evaporator F, section C, into section D and then discharge it horizontally from grille 38, that 45 we have provided means whereby the air may be discharged into the room fan-like; that we have provided a drip pan for catching the drippings from the evaporator and by referring to Figure 9 it will be noted that the drippings from the drip 50 pan will be conducted into a tank into which the condenser is positioned, the tank being supplied with an inlet valve which is thermally controlled and an overflow pipe thus to insure condensation of the compressed gasses as will hereinafter appear.

In Figures 3, 4, 8 and 9 we illustrate a modification wherein the bottom section comprises side panels 60 and 61, each having removably secured grilles 62 and 63 at their bottoms and front and rear panels 64 and 65. The bottom of this unit is designated by reference numeral 66.

We provide spaced partition walls 67 and 68 which are secured to front and rear panels 64 and 65 and to member 66 at their bottoms and terminate at their tops as at 69.

We provide an insulated wall 70, thus forming a chamber 11 which is closed at its front by a removably secured panel or door 72. Thus we provide an inclosure or compartment into 70 which we position the compressing and condensing apparatus, the removable door 72 providing easy access thereto.

We provide a drip-pan 73 which is positioned as indicated in Figures 3 and 4 forming the 75 bottom of the evaporator chamber, the evapor-

ator and other connected parts being designated by numerals which are similar to the numerals used in Figures 1 and 2. Chamber 11, however, differs in that side panels 60 and 61 and drip pan 73 act to form outlets 75 to air ducts 76 which extend from the grilles 62 and 63 to these outlets 75.

We provide eliminators 77 which are positioned to thereby direct the drippings into the pan. We provide a drain pipe 78 for pan 73 which preferably drains into the condenser tank, as will hereinafter appear. We preferably provide air filter pads 80 and position these pads as illustrated in Figure 3, thus to filter all of the air that enters the unit.

The condenser apparatus is similar to the apparatus positioned in member E and preferably consists of a motor 81 and a compressor 82; the compressor having a pipe 83 which leads to condenser coil 84; the condenser coil being positioned in tank 85 into which pipe 78 drains; coil 84 having an operating connection 86 to the evaporator coils F; these coils having an operating connection 87 to compressor 82. Tank 85 is provided with an overflow pipe 88 and a thermally controlled valve 89, the valve having a pipe connection to the source of water supply 90 and an outlet 91 into tank 85; thermally controlled valve 89 being adapted to maintain a desired 30 temperature of the water in the tank, thus if the water from the drip pan is insufficient for cooling purposes, additional water will be supplied by valve 89, the surplus being permitted to overflow through pipe 88, thus there will be maintained a suitable cold liquid bath for condenser coils 84. 35

Duct 18 provides a suitably sized space for the reception of a steam heater coil for winter service illustrated in Figure 9 and designated by reference character G.

Thus it will be seen by scrutinizing Figures 3, 4 and 8 that the air passes from the floor level into the unit and out of the unit near the ceiling and circulates through the room somewhat as illustrated in Figure 8, the unit being preferably positioned adjacent one of the walls and in the center and the blades 45 bent so that the air is discharged from the front grille fan-like and from side grilles 47 which are preferably provided in section D.

Thus by a proper position of blades 45 the entire ceiling surface of the room may be swept by the discharged conditioned air and naturally it will pass downward over the entire surface of the room in a manner which will not be perceptible to the occupants.

This design is particularly useful when a steam coil is used for cold weather because the floor will be kept warm by the passage of the heated air on its return to the unit. For this reason the designs shown in Figures 3, 4, 8 and 9 are preferable. By scrutinizing Figure 9 it will be seen that the air is directed through the unit in a very efficient manner.

Thus it will be seen that we have provided a simple, easily manufactured, easily shipped and erected self contained air conditioning cabinet which may be positioned in a room and adjusted so as to efficiently condition or heat the air and move it through the room for maximum comfort to the occupants.

By referring to Figure 3 it will be seen that unit E may be positioned in chamber 11 in lieu of the arrangement of parts in this chamber as illustrated in Figures 3 and 9. And when this is done, partitions 67 and 68 may be dispensed with 75

and the air caused to move upwardly through the entire bottom compartment and in contact with member E and then into the evaporator compartment similar to the design shown in Figures 5 3 and 9 as illustrated by arrows.

Clearly many minor detail changes may be made without departing from the spirit and scope of the present invention as recited in the appended claims.

10 Having thus shown and described our invention, we claim:

1. An air conditioning device of the class described, comprising an elongated vertically positioned housing being rectangular in cross section and having a width considerably greater than its depth and being separated into three or more compartments one above the other, spaced vertical partitions in the bottom or first compartment extending from the front to the rear panel thereof and having a cover forming a supplemental compartment and side air ducts for its length, an access door in said supplemental compartment, a drip pan on the top of said supplemental compartment terminating transversely at the outlet end of said air ducts, a compressor unit positioned in said supplemental compartment, a tank in said supplemental compartment having the condenser coil therein, a drain connection from said drip pan leading into said tank, means for maintaining the desired temperature of the cooling water in said tank, grille inlets in said air ducts near the bottom thereof, an evaporator coil positioned in the top of said second compartment having an air outlet into the third compartment and an air directing duct therearound the bottom of which terminates a distance above said pan, means between said duct and pan adapted to direct the condensate into the pan, a blower fan in said third compartment having inlets therefrom and an outlet into the room served.

2. A device as recited in claim 1 including; said fan outlet having spaced inwardly extending vertically positioned blades their outer edges being anchored and adapted to be bent to thereby discharge the air in any desired direction or fan-like.

3. A device as recited in claim 1 including; said last two chambers being detachably secured together and to said first chamber.

4. An air conditioning device of the class described, comprising an elongated vertically posi-

tioned housing being rectangular in cross section and having a width considerably greater than its depth and being separated into three or more compartments one above the other, spaced vertical partitions in the bottom or first compartment extending from the front to the rear panel thereof and having a cover forming a supplemental compartment and side air ducts for its length, said air ducts having inlets at their bottoms and outlets into the compartment next 10 above said supplemental compartment, a compressor and condenser mechanism in said supplemental compartment, an evaporator positioned in said compartment next above said supplemental compartment and having an air outlet into 15 the adjacent or third compartment, the compartment positioned next above said evaporator compartment having therein a blower fan with inlets therefrom, a top chamber receiving the outlet of said fan and having outlet grilles into 20 the room served, a drip catching means positioned below said evaporator coil and having means whereby all of the drippings caused by said evaporator will be caught thereby.

5. A device as recited in claim 4 including; 25 filter pads in said air ducts positioned above said inlet grilles whereby all of the circulating air must pass therethrough.

6. An air conditioning device of the class described, comprising an elongated vertically positioned housing being rectangular in cross section and having a width considerably greater than its depth and being separated into three or more compartments one above the other, spaced vertical partitions in the bottom or first compartment extending from the front to the rear panel thereof and having a cover forming a supplemental compartment and side air ducts for its length, an access door in said supplemental compartment, means forming a drip pan on 30 the top of said supplemental compartment, a compressor unit positioned in said supplemental compartment, said air ducts having outlets into said second compartment and inlets at their bottoms, an evaporator unit positioned in the top 35 of said second compartment having an operating connection to said compressor unit and an air outlet into said third compartment, a blower fan in said third compartment having inlets therefrom and an outlet into the room served. 40
